Primary Examiner — Kevin K Rudzinski(74) Attorney, Agent, or Firm — GIBRALTAR CONSULTING LLC; Tariq S. S. Najee-Ullah(57) CLAIM

The ornamental design for a backwards haircutting cape as shown and described.

DESCRIPTION

FIG. 1 is a perspective view of a backwards haircutting cape showing our new design in an open position;

FIG. 2 is a top plan view looking down on the top side thereof in an open position;

FIG. 3 is a bottom plan view of the invention looking down on the bottom side shown in an open position of the shown;

FIG. 4 is a side elevation view of the invention thereof;

FIG. 5 is a front view of the invention thereof being worn in an open position;

FIG. 6 is a front view of the invention thereof being worn in a closed position; and,

FIG. 7 a rear view of the invention thereof being worn in a closed position.

In the drawings, the broken lines depict environmental subject matter and form no part of the claimed design. The small broken lines illustrate stitching that forms part of the claimed design.
